UNITED STATES PATENT OFFICE

129,963

DESIGN FOR A COOKING VESSEL

William Eck, Manitowoc, Wis., assignor to Wisconsin Aluminum Foundry Co., Inc., Manitowoc, Wis.

Application January 17, 1941, Serial No. 98,153

Term of patent 14 years

To all whom it may concern:

Be it known that I, William Eck, a citizen of the United States and resident of Manitowoc, in the county of Manitowoc and State of Wisconsin, have invented a new, original, and ornamental Design for a Cooking Vessel, of which the following is a specification, reference being had to the accompanying drawing, forming part thereof.

ing vessel, looking toward the handle, showing my new design;

Figure 2 is a top plan view; and

I claim:

The ornamental design for a cooking vessel, as shown.

WILLIAM ECK.
